UNITED STATES PATENT OFFICE.

JAMES M. BRONSON, OF KANSAS CITY, MISSOURI.

BOOK-COVER.

SPECIFICATION forming part of Letters Patent No. 366,918, dated July 19, 1887.

Application filed August 17, 1886. Serial No. 211,142. (No model.)

To all whom it may concern:

Be it known that I, JAMES M. BRONSON, of Kansas City, in the county of Jackson and State of Missouri, have invented a new and 5 Improved Book-Cover, of which the following is a full, clear, and exact description.

Reference is to be had to the accompanying drawings, forming a part of this specification, in which similar letters of reference indicate corresponding parts in all the figures.

Figure 1 is a perspective view, with parts broken away, of a book provided with my improved cover. Fig. 2 is an end view of the same, showing the book open; and Fig 3 is an 15 end view showing the book closed. Fig. 4 is a sectional view of the hinge of the cover.

The book-back A is made in the form of a segment of a hollow cylinder in the usual way, and the edges B of the book-covers C are connected with the back by flexible strips a of leather or other suitable material. The body D of the book is made in the usual way, and each cover C is provided with a metal plate, E, secured to its inner surface and projecting be- 25 yond the inner edge, B, of the cover. The projecting edge of each strip is inclosed between strips c c' of parchment glued together and to the metal plate and glued to the cover. The parchment is secured to the back of the 30 body D of the book and forms the connection between the body and cover. The hinge-joint E thus made allows the body of the book to open, so as to cause the leaves to lie flat down upon the covers, as shown in Fig. 2.

The covers C of the book are connected with 35 each other at the ends of the book-body by a stay consisting of a spiral spring, d, connected with plates e, secured to the covers by links f and clips g.

By means of my improvement the book is 40 allowed to open perfectly flat without straining the joints of the book or cover, the springs causing the drawing together of the inner edges of the covers and the consequent elevation of the middle portion.

Having thus described my invention, what 45 I claim as new, and desire to secure by Letters Patent, is—

1. The combination, with the book-covers, the back and the flexible connections between 50 the back and covers, of the stiff plates or strips connecting the covers and body of the book and a stay connecting the covers near the back, substantially as set forth.

2. The combination, with the covers and the 55 back of the book, of an elastic stay connecting the covers near the back, substantially as set forth.

3. The combination, with the back A and 60 covers C, of the plates e, springs d, links f, and clips g, substantially as specified.

JAMES M. BRONSON.
